ICE CUBE TRAY

Logan L. Mallard, Norfolk, Va.

Application August 22, 1940, Serial No. 353,728

10 Claims. (Cl. 62—108.5)

This invention relates to an ice cube tray of the type designed to be placed in a domestic refrigerator and in which ice cubes are frozen. More particularly, this invention relates to an ice cube tray having a grid member in which the partitions thereof are relatively movable in order to cause enlargement of the freezing cells to more easily release the cubes of ice contained therein.

This application is a continuation in part of my previous applications, Ser. Nos. 204,646 and 239,723.

An object of this invention is to provide a grid for an ice tray from which the ice may be quickly and easily ejected after removal of the grid and ice from the tray. A further object is to provide an improved grid member in which the longitudinal partition is articulated to permit bowing thereof after removal of the grid from the tray, so as to enlarge the freezing cells and thus release the ice.

A further object is to provide stop members at each joint of the articulated longitudinal partition in order to cause a uniform bowing of this partition throughout its length so that each freezing cell will be equally enlarged and the ice cubes thus more easily released.

A still further object of the invention is to provide means on the transverse partitions to position these partitions in such a location as to bisect the angle formed by adjacent edges of adjacent segments of the longitudinal partition when the latter partition is in bowed position. A further object of this invention is to provide separate and distinct operating devices for disengaging the grid and ice from the tray, and for bowing the grid and ejecting the ice cubes.

Fig. 1 is a longitudinal view, partly in vertical section, of the tray and grid, and showing the grid in bowed position;

Fig. 2 is a fragmentary horizontal section taken through the pivots of the longitudinal partition of the grid;

Fig. 3 is a detailed view of one of the longitudinal segments, showing the connecting links;

Fig. 4 is a detailed view of one of the transverse partition members;

Fig. 5 is a fragmentary section similar to Fig. 1 of a modified form of my invention in which the links are made integral with the segments;

Fig. 6 is a view similar to Fig. 2 of the modification shown in Fig. 5;

Fig. 7 is a detailed view similar to Fig. 3 of the modification shown in Fig. 5.

The tray 10 is a conventional ice tray, made of good heat conductive material, preferably alumi-

num, and designed to be placed in a domestic refrigerator and to have ice frozen therein. The grid 11 has a longitudinal partition formed of a plurality of segments 12 and 13. These segments are interconnected by links 17 lying along each face of segments 12 and 13 to retain the segments in a single plane. The mounting of the links 17 on the segments 12 and 13 is such as to provide for a relative pivotal movement between the various segments, which results in an articulated strip or partition capable of being bowed upon the application of a suitable force.

Hook-like extensions 14 are provided on the upper edge of the segments 12 and 13, which project in the same plane as and beyond the segments upon which they are mounted, and above the adjacent segment, terminating a short distance above the upper edge of the adjacent segment when the longitudinal partition is in an unbowed position.

In assembling the grid 11, one of the transverse partitions 16 is placed between each adjacent segment of the longitudinal partition. This is accomplished by passing the links 17 through the slot 27 formed in the central portion of the partitions 16. The links 17 are pivotally secured to the segments 12 and 13 by rivets or other suitable securing devices 20. The connection of links 17 to segments 12 and 13 is such that the segments may freely pivot on the rivets 20.

A horizontally extending portion 15 is formed at the top central portion of the transverse member 16. This horizontal portion is adapted to lie between the upper edge of one adjacent segment 12 and the hook-like portion 14 of the other adjacent segment. The horizontally extending portion 15 is turned downwardly at the end, and a slot 28 is provided therein to engage the upper edge of the segment 12 and maintain the partitions 16 perpendicular to the longitudinal partitions 12 at all times.

The end segments 13 of the longitudinal portion are provided with an outwardly extending portion adapted to overlie opposite marginal edges of the tray 10. Foot members or ejectors 21 are pivotally secured to these portions by rivets or other suitable securing devices 22. A lever 23 is pivotally secured to the upper portion of one of the ejectors 21 by means of a suitable fastener 24. A second lever 25 is pivotally secured to the lever 23 near the pivoted end thereof. A link 26 is pivotally secured at one end to the upper portion of the other ejector 21, and at the other end to the lever 25 near the pivoted end thereof. The linkage is so proportioned that

when the grid is lying in the tray, the link 26 will overlie the hooked portions 14 of the longitudinal partition. In this position the lever 25 will nest horizontally about link 26, and the lever 23 will nest horizontally above both the lever 25 and the link 26.

When it is desired to remove the ice and grid from the tray 10, the lever 23 may be pivoted from horizontal to vertical position, the lever 25 remaining in a substantially horizontal position adjacent the link 26. This movement will draw the upper portions of the ejectors 21 towards each other, causing these ejectors to pivot about the pin 22 relative to the segments 13; thus projecting the bottom surface of the ejectors 21 firmly against the marginal rim of the pan 10 and forcing the grid and ice upward as a unit.

After the ice has been loosened from the pan, the lever 25 may then be raised to substantially vertical position coinciding approximately with the position of the lever 23. This will result in drawing the projecting portions of the segments 13 towards each other, and will cause the articulated longitudinal partition composed of the segments 12 and 13 to pivot on the rivets 20 and assume a bowed contour as shown in Fig. 1. The amount of relative rotation between the segments, or bowing, is controlled by the hook-like portions 14 of the segments 12 and 13, which act as stops to limit the relative rotation.

Since the substantially horizontal portion 15 of each transverse partition 16 lies between the end of the hooked portion 14 and the upper edge of the adjacent segment 12, it is thus firmly seized between the outer end of the hook-like portion 14 and the upper edge of the adjacent segment 12. The precise angle between the horizontal portion and the vertical portion of the partition 16 is such that when the grid is in full bowed position, each of the transverse partitions 15 will approximately bisect the angle formed by the adjacent vertical edges of adjacent segments 12. It will be noted that there is sufficient clearance between the links 17 and the rectangular slot 27 to allow a limited pivotal rotation of the partition 16 about the links 17 in the plane of the longitudinal partition.

A further modification is shown in Figs. 5, 6, and 7, in which extensions 18 and 19 are formed integral with the segments 12, see Fig. 7, to take the place of the links 17. In this event the adjacent segments of the longitudinal partition are mounted in overlapping relation as shown in Fig. 6 so as to form substantially a single plane made up of a multiplicity of overlapping units.

As a further modification of either form, the horizontal projection of the transverse partition 16 may be formed as shown in Fig. 5 without a vertical portion at the end thereof. In this event I prefer to slot the horizontal projection and engage it with the hook-like extension 14 of the adjacent segment in order to keep the partition 16 in alignment. It is usually desirable to form an extended terminus on the hooklike portion 14 in order to assure engagement with the upper edge of adjacent segments 12 when the longitudinal partition is bowed, as shown in Figs. 5 and 7.

It will be seen from the foregoing description that I have provided an ice tray grid in which the ice is quickly and easily loosened by deforming the grid to break the bond between the grid and the ice. This deformation is accomplished not by the bending of any portion of the grid, 70

but by providing for relative movement between the various units of the grid. By providing a series of stops to limit the bowing movement of the longitudinal partition and by providing extensions 15 on partitions 16, I have provided a grid in which, when bowed, each ice cell will be substantially equally increased in size so as to easily and completely break the bond between the grid and the ice.

10 The relative movement between the segments 12 and the links 17 or the extensions 18 and 19 of the adjacent segments further serves to break the bond between the ice and the grid partitions, as described in my copending application Ser. 15 No. 239,723.

The provision of the two levers 23 and 25 permits first breaking the bond between the ice and the tray, and, subsequently breaking the bond between the ice and the grid, thus producing an ice grid that is more easily operated and with the expenditure of less energy since the ejection of the ice and grid and the bowing of the grid are two separate and distinct operations.

It will be obvious to those skilled in the art that various changes may be made in this device without departing from the spirit of the invention and therefore the invention is not limited to what is shown in the drawing and described in the specification but only as indicated in the 30 appended claims.

What is claimed is:

1. In a grid for an ice tray, a series of segments pivotally connected to each other forming a longitudinal partition, a series of transverse partitions mounted for pivotal movement on the upper portion only of said longitudinal partition and forming with said longitudinal partition and the tray a series of freezing cells, means for limiting the relative movement between segments 35 of said longitudinal member, and means engaged by said first named means for limiting the pivotal movement of said transverse partitions.

2. In a grid for an ice tray, a series of segments forming a longitudinal partition, said segments being in overlapped relation and each having an extension on the side thereof pivotally connected to the next adjacent segment, transverse partitions lying between the segments of said longitudinal partition, means for causing a limited rotation in an upright plane of each of said segments, and means, including hook-like projections extending upwardly from said segments, for limiting relative rotation thereof.

3. In a grid for an ice tray, a series of segments lying substantially in a single plane and together forming a longitudinal partition, a series of transverse partitions lying between said segments, means pivotally connecting said segments to each other, means, including slotted projecting portions of said transverse partitions, for maintaining said transverse partition perpendicular to said longitudinal partition, and extensions of said segments, for limiting the relative rotation of said segments.

4. In a grid for an ice tray, a series of linked segments forming a longitudinal partition, a transverse partition lying between each pair of adjacent segments forming together with said longitudinal partition and the tray a series of freezing cells, and means including hook-like projections extending upwardly from the upper edge of said segments for limiting the relative rotation of said segments.

5. In a grid for an ice tray, a series of segments pivotally connected to each other forming

a longitudinal partition, a series of transverse partitions pivotally mounted on the upper portion of said longitudinal partition and forming with said longitudinal partition and the tray a series of freezing cells, hook-like members formed on the upper portion of said segments in a manner such as to bear upon the segment adjacent thereto upon bowing said longitudinal partition in order to limit the bowing movement thereof, and longitudinal projections formed on the upper portion of said transverse partitions and adapted to lie between the hook-like portion of one segment and the upper portion of the adjacent segment to position said transverse partition upon bowing said longitudinal partition.

6. In a grid for an ice tray, a series of pivotally connected segments forming a longitudinal partition, a series of transverse partitions, projections formed on the end segments of said longitudinal partition and adapted to overlie the marginal walls of the tray, means pivotally mounted on each of said projections, and adapted when pivoted to eject said grid, and means for bowing said grid to eject ice cubes therefrom, said means comprising a lever pivoted to one of said ejecting means, a second lever pivoted to said first lever, and means linking said second lever and said other ejecting means.

7. In a grid for an ice tray, a series of segments pivotally connected to each other forming a longitudinal partition, a transverse partition lying between each pair of said segments mounted for movement with certain of the latter, a hook-like portion formed on the upper edge of each of said segments and overlying the segment adjacent thereto, and projections on the upper portion of said transverse partitions lying between said hook-like portion and the next adjacent segment, said hook-like portion serving to limit the relative rotation of said adjacent segments. 40

8. In a grid for an ice tray, a series of segments pivotally connected to each other forming a longitudinal partition, a series of transverse partitions pivotally mounted on the upper portion of said longitudinal partition and forming with said longitudinal partition and the tray a series of freezing cells, and hook-like members formed on the upper portions of at least certain of said segments in a manner such as to bear against the segments adjacent thereto upon bowing said longitudinal partition in order to limit the bowing movement thereof.

9. In a grid for an ice tray, a series of segments connected to one another for pivotal movement about their upper extremities and lying in a single plane and together forming a longitudinal partition, a series of transverse partitions lying between said segments and mounted for movement with certain of the latter, means pivotally connecting said segments, and means limiting the relative rotation of said segments, said latter means comprising hook-like projections extending from the top portions of at least certain of the segments and overlying the segments next adjacent thereto.

10. In a grid for an ice tray, a series of segments pivotally connected to each other in the region of their upper extremities and forming a longitudinal partition, a transverse partition lying between each pair of said segments, said transverse partitions being mounted for pivotal movement about their upper extremities, and a hook-like projection formed on the top of each of said segments and overlying the upper edge 35 of the segment adjacent thereto to limit the relative rotation therebetween, each of said hook-like projections terminating in a flange overlying the adjacent transverse partition.
